UNITED STATES PATENT OFFICE.

WILLIAM CANNELL, OF SPRINGFIELD, MASSACHUSETTS, ASSIGNOR TO BAUSH
MACHINE TOOL COMPANY, A CORPORATION OF MASSACHUSETTS.

UNIVERSAL JOINT.

1,159,176.

Specification of Letters Patent.

Patented Nov. 2, 1915.

Application filed June 18, 1914. Serial No. 845,811.

To all whom it may concern:

Be it known that I, WILLIAM CANNELL, a subject of Great Britain, and a resident of Springfield, Massachusetts, have invented certain new and useful Improvements in Universal Joints, of which the following is a specification.

This invention aims to provide an improved universal joint of the simplest construction, which is easily put together and has the minimum of parts.

The accompanying drawings illustrate an embodiment of the invention.

Figure 1 is a longitudinal section through the dust case, showing the joint in side elevation; Fig. 2 is a rear end elevation of one of the forks; Fig. 3 is a transverse section through one of the prongs of a fork on the line 3-3 of Fig. 1; Fig. 4 is an end elevation of the center block; Fig. 5 is a side elevation of the same; Fig. 6 is a central longitudinal section of the same.

Referring to the embodiment of the invention illustrated a center block is provided having a pair of grooves A in one longitudinal plane and a similar pair of grooves A' in a longitudinal plane at a right angle to that of A, A'. The two forks are identical, one having a pair of prongs B, B fitting in one of the two pairs of grooves A, A and the other having similar prongs B' fitting in the grooves A' of the center block and extending beyond the center of the block so that when the joint is assembled as in Fig. 1 the block is embraced between the prongs of each of the forks and held against longitudinal movement. This construction, since it prevents separation of the block in the normal position also prevents introduction of the prongs of the fork upon the block in the normal position of the parts. In order to permit such introduction the block is made shorter than the diameter of the grooves, and so that its length is less than the space between the extremities of each fork. The length of the block in fact is made such that by turning a fork to the right angle position shown in dotted lines at C, Fig. 1, or to any similar abnormal position the block may be introduced into the space within the prongs and there turned to lock it in the normal position.

After one of the forks has been introduced upon the center block and turned to its nor-

mal position the other fork can be introduced only by passing one of its prongs through the space between the center block and the fork which is already in position. For example, the fork shown in dotted lines at C, Fig. 1, can only be introduced by 55 passing one of its prongs between the prongs B' of the right hand fork already in position. To make such introduction possible the forks are designed so that the space D between the end of the block and the adjacent portion of the fork shall be sufficiently wide to permit the passage of a prong of the second fork. The forks are designed, as shown in Fig. 3, with ribs E on their inner faces fitting within the grooves 60 of the center block and with a laterally extending outer portion F. The ribs E are terminated at such a point as not to interfere with the introduction of the second fork and the outer portion F of the forks is cut 65 away as indicated at G for the same purpose.

The stems of the forks may constitute directly sections of the shaft which are to be united by the universal joint. Preferably, 70 however, such stems H, H' constitute hubs with squared recesses as shown in Fig. 2 for attachment to the ends of the shaft sections.

When the parts are assembled as in Fig. 1 85 a certain angular motion of the shaft sections is permitted, sufficient for the purposes desired, without turning the sections to a sufficient angle to release the forks from the center block. A spherical casing is then 90 applied to the joint comprising a segmental shell J extending slightly beyond the center of the joint, and a segmental shell K overlapping the edge of the shell J. This casing serves to keep out dust so as to assure durability of the joint. It is also made to serve the purpose of locking the parts of the joint. For this purpose the shell K is formed with a shoulder L at such a point that when any one of the forks is turned 95 to an extreme angle the edge of the shell J will strike the shoulder L and prevent further angular movement. This occurs before the angular movement has been sufficient to release the fork from the center block. The 100 casing, therefore, holds the parts in their assembled position while permitting all the 105 freedom of movement which is required.

The shell constituting the two parts of the casing are fastened on the stems of their respective forks in such a way as to be easily removable. For this purpose each of the 5 stems H and H' is provided with an annular groove and a split spring ring M is introduced into said groove and projects outward beyond the surface of the stem so as to prevent any backward movement of the 10 shell; the two locking rings M being located at such points as to hold the two shells J and K fitting closely against one another at their overlapping portions. The center block is preferably of the spider-like construction shown in Figs. 4, 5 and 6. It may, however, be made in a great variety 15 of designs. As illustrated the circular grooves are formed in four heads N which are segments of cylinders, and the lengths 20 of which are such as to give a long bearing for the forks in all practical angular positions. The four heads N are connected by short straight connecting members O which are of less thickness than the lengths of the 25 heads and are spaced apart from each other, and which serve to transmit the circular strains from one head N to the next and thus from one fork to the other, without the excess of metal which is provided where solid 30 spherical balls are used as center blocks. The omission of metal from the center and from the outer portions of the blocks between the heads N leaves the metal only 35 along the lines O where it is most efficiently located to carry the strains and, therefore, results in a block which combines the greatest lightness with the desired strength.

Though I have described with great particularity of detail a certain specific embodiment of my invention yet it is not to be understood therefrom that the invention is restricted to the particular embodiments disclosed. Various modifications thereof in detail and in the arrangement of the parts 40 may be made by those skilled in the art without departing from the invention as defined in the following claims. The principle 45 of the invention may be applied also to the connection of a single fork with the center block, the connection of the opposite shaft section being made in other ways.

What I claim is—

1. A universal joint having parts which are adapted in normal operation to be turned at different angles relatively to each other within a limited range and adapted to be separated when turned beyond said range and a locking means extending around said joint and consisting of two parts attached to said parts of the joint and adapted to partake of relative angular movement to only a limited extent within said range. 55

2. A universal joint having parts which are adapted in normal operation to be turned at different angles relatively to each other 60 within a limited range and adapted to be separated when turned beyond said range, a dust guard inclosing said joint and consisting of two spherical parts J and K overlapping each other and adapted to partake 70 of relative angular movement, one of said parts of the dust guard having a shoulder adapted to be engaged by the other to limit the angular movement within said range.

3. A universal joint having parts which 75 are adapted in normal operation to be turned at different angles relatively to each other within a limited range and adapted to be separated when turned beyond said range, a locking means extending around said joint 80 and consisting of two parts applied to said parts of the joint and adapted to partake of relative angular movement to only a limited extent within said range, and spring devices detachably connecting the two parts 85 of said locking means to the respective parts of the joint.

4. A universal joint including in combination a center block having circular grooves 90 in longitudinal planes and comprising heads N in which said grooves are formed and connecting members O spaced apart from each other and extending directly between the adjacent heads.

In witness whereof, I have hereunto 95 signed my name in the presence of two subscribing witnesses.

WILLIAM CANNELL
